BOLSTER SUPPORTING MECHANISM

Marchand B. Hall, Chicago, Ill., assignor to
Cardwell-Westinghouse Company, Chicago,
Ill., a corporation of Delaware

Application May 1, 1933, Serial No. 668,684

6 Claims. (Cl. 267—9)

This invention relates to shock absorbers, and, more particularly, to bolster supports for railway car trucks.

One of the objects of the invention is the provision of a new and improved combined spring and friction shock absorber for use on railway car trucks.

Another object of the invention is the provision of new and improved railway car bolster support having novel means for maintaining the spring seats in parallel relation during the operation of the device.

A further object of the invention is the provision of a new and improved shock absorber in which the resistance increases rapidly upon compression of the device and in which the rebound is damped.

A further object of the invention is the provision of a new and improved shock absorbing device that is simple in construction, inexpensive to manufacture and install, efficient in operation and not likely to become broken or out-of-repair.

Other and further objects and advantages of the invention will appear from the following description taken in connection with the accompanying drawing, in which—

Fig. 1 is a side elevation of a portion of a railway car truck showing the invention in position thereon, with parts broken away;

Fig. 2 is a vertical section of the device;

Fig. 3 is a section on the line 3—3 of Fig. 2;

Fig. 4 is a perspective view of the sleeve friction member; and

Fig. 5 is a view similar to Fig. 2, but showing a modified form of construction.

In the use of bolster springs of the combined friction and resilient type on railway cars, it is not uncommon under certain conditions for the upper spring seat to assume an angular position relative to the lower spring seat, and thereby unequally distribute the load on the spring. The present invention seeks to remedy this difficulty by the provision of means for automatically positioning the spring plates at the ends of the gear whereby the plates will remain substantially parallel during the use of the device.

Referring now to the drawing, the reference character 10 designates generally a railway car truck having a side frame 11, lower arch member 12 and pedestals 13 and 14, as is usual in such constructions. Vertically slideable between the pedestals 13 and 14 is the bolster 15 which is supported by the bolster supporting units 16 inserted between the spring plank 17 and the bolster supporting unit. Each bolster supporting unit com-

prises a friction device 18 and a spring 19. The friction device comprises two frictionally engaging telescopic members. This device includes a lower section 21 comprising a base plate 22 which is adapted to be seated on the spring plank 17 and a cylindrical hollow member 23 rigidly secured to said plate and extending upwardly therefrom.

The interior surface of the cylindrical member 23 tapers downwardly to form a friction surface, as will presently appear. The plate 22 is provided at its central portion with an upstanding hollow projection or boss 24 extending upwardly within the cylindrical member 23 and having an axial opening 25 through which a retaining bolt 26 extends.

Suitable means are provided for frictionally engaging the tapered surface 27 of the cylindrical member 23. In the form of construction selected to illustrate one embodiment of the invention, a split sleeve element 28 is employed for this purpose. The sleeve element is tapered toward its lower end to conform to the inner surface of the cylindrical member 23 with which it frictionally engages. In order that the upper portion of the sleeve that does not contact the tapered surface of the cylindrical member shall contract with the lower portion that does contact said surface when the sleeve is depressed, the sleeve is made slightly thinner adjacent its upper end as at 30. In order that all portions of the sleeve shall bend equally when the same is contracted, the portions of the sleeve adjacent to the slot 29 are made comparatively thin as at 31 and 32 and the sleeve increases to its maximum thickness directly opposite the slot, as at 33.

The sleeve element 28 is provided with a plurality of radially extending bearing lugs or projections 34 at its upper end. These lugs or projections are adapted to support a cap member or supporting plate 30 which in turn supports the bolster 15 of the truck. Whatever inclined position the supporting plate may be caused to take by the weight or force applied to said plate, it is desirable that the same continue to bear on all of the lugs 34 to prevent tilting of said sleeve during its depression.

In order that the sleeve member 28 shall not be tilted in its vertical movement during use even though the bolster should tilt or rock, suitable means are provided for compensating for any tilting or rocking of the bolster. In the construction shown, the projections or lugs 34 are provided with curved surfaces on their upper sides. These curved surfaces are so constructed

that they will remain in contact with the plate 30 even though said plate be tilted. In other words, the curved surfaces of these lugs constitute in effect portions of a sphere or ball with said surfaces curving downwardly toward the outer ends of said lugs.

The supporting plate or member 30 for supporting the car bolster 15 comprises a plate 37 having its central portion depressed to form a hollow cylindrical projection or boss 38 having an axial opening 39 therein through which the bolt 26 extends, as shown in Fig. 2 of the drawing. In the operation of the device, the contraction of the sleeve member 28 necessarily causes the lugs 34 to move relative to the under surface of the supporting plate 30 and in order that the lugs shall move evenly, means are provided to offer a minimum resistance to this movement. In the form of construction shown, which is by way of example only, the plate 37 is provided with an annular inclined surface 41 extending about the boss 38. This surface is adapted to be engaged by the curved surfaces 35 of the lugs 34 when the bosses are assembled. The inclined surfaces 35 on the lugs 34 engaging the inclined surfaces 41 on the plate tend to assist the contraction of the sleeve 28 when the bolster is forced downwardly. The lugs 34 are symmetrically arranged with reference to the split in the sleeve, whereby the two lugs adjacent the split will move uniformly during the compression of the unit.

A spring seat 42 having a horizontal portion 43 and a vertical peripheral flange 44 extends about the upper end of the sleeve element 28 and is adapted to engage the lower surface of the lugs 34. The flange 44 is adapted to engage the lugs 35 for positioning the seat on the sleeve element. The spring 19 is inserted between the spring seat 43 and the lower base plate 22 for returning the boss to normal position after compression. When the parts are in operative position, as shown in Figs. 1 and 2, and the bolster is depressed, the unit is compressed by causing the sleeve 28 to slide downwardly into the cylindrical member 21, and since the opening in said member tapers downwardly, the sleeve 28 will be compressed radially. The resistance to compression of the sleeve will develop considerable friction between the contacting surfaces of the sleeve 28 and cylindrical member 21. This frictional resistance together with the resistance to compression of the spring 19 will absorb the shock and will check and finally stop the downward movement of the bolster 15. During the downward movement of the sleeve element it will contract, thus causing the lugs 34 adjacent to the slot 29 to move inwardly. The inclined surface 41 on the supporting plate 30 with which the lugs 34 engage will facilitate this movement. The spring 19 which has sufficient capacity to return the parts to normal position after compression will react when the bolster reaches the limit of its downward movement after each shock. The capacity of the unit may be varied within extremely wide limits. By tapering the sleeve element 28 and its cooperating friction surface 27 in the cylindrical member 21 at an angle more acute, the capacity is increased materially. Making this angle less acute decreases the capacity. With the increase in the acuteness of the angle, the capacity of the spring 19 should also be increased, as otherwise a point may be reached where the wedging action may become so great that upon release the spring may not possess sufficient energy to release the friction elements.

The parts are preferably so constructed that the units are interchangeable with the conventional springs that are at present employed for supporting the truck bolster.

In the form of construction shown in Fig. 5, this construction differs from that just described in that the base plate is separate from the remaining elements. As shown, the supporting plate 46, the spring seat 47, the split friction sleeve 48, the bolt 49 and the spring 51 are substantially the same as the construction shown in Fig. 2. The base member 52 is provided with a hollow boss 53 having an axial opening therein for receiving the lower end of the bolt 49. Extending about the boss 53 is a recess 54 having a curved or concave wall 55 on which is seated the lower end of a friction sleeve 56. The friction sleeve 56 is provided with a plurality of radial projections 57 which correspond to the radial projections 35 of the sleeve member 28. These projections are provided with curved lower surfaces 58 which are adapted to engage the curved or concave wall 55. A spring seat 59 is interposed between the spring 51 and radial projections 57. In the operation of the device, the radial projections 57 and curved or concave wall 55 perform the function of a ball and socket joint which will permit a slight angular movement of the friction sleeve 56 relative to the base plate 52, thereby insuring the parallelism of the plates 46 and 52 under all conditions.

The spring 51 is placed in position under tension and in the operation of the device the spring will tend to restore the parts to normal position after the device has been compressed, and will also tend to restore the parts to normal position after the plate 46 has been moved laterally relative to the plate 52.

It is thought from the foregoing taken in connection with the accompanying drawing that the construction and operation of my device will be apparent to those skilled in the art and that changes in size, shape, proportion and details of construction may be made without departing from the spirit and scope of the appended claims.

I claim as my invention:

1. A railway truck bolster supporting unit comprising an upper plate having surfaces on its lower side inclined upwardly and inwardly, a lower plate, telescopic friction elements between said plates, one of said elements having a plurality of laterally projecting arms on its upper end, said arms having their upper surfaces extending outwardly and downwardly for engaging said inclined surface and a spring between said plates for returning the parts to normal position after release.

2. In a railway truck bolster supporting unit, an upper plate, a lower plate, a cylindrical hollow member rigidly secured to and extending upwardly from said lower plate, the interior walls of said member tapering downwardly, a tapered split sleeve element telescopically mounted in said member and frictionally engaging the same, the upper end of said element having laterally extending means engaging said upper plate, a spring surrounding said member and element and seated on said lower plate, and a spring seat having an annular horizontal portion interposed between said spring and said means, said seat provided with an upstanding flange about its periphery for engaging said means for positioning said seat.

3. In a railway truck bolster supporting unit, a

base plate having a cylindrical member extending axially upward therefrom and having an axial opening therein tapering downwardly, a perforated hollow boss extending upwardly within 5 said member, a top supporting plate having a perforated hollow boss extending downwardly from its central portion, a tapered split sleeve member frictionally engaging said tapered opening and engaging said top supporting plate, a 10 spring seated on said base plate and surrounding said cylindrical and sleeve members, a spring seat between said spring and supporting plate and in engagement with said spring, means on said sleeve engaging said spring plate, and a 15 bolt extending through the perforations of said bosses for limiting the expansion of said unit.

4. In a bolster spring construction, a lower plate forming a spring seat, said plate having a raised hollow boss provided with an axial opening 20 in its bottom wall, a cylindrical friction element surrounding said boss and extending upwardly beyond the same, said element having its inner surface tapering downwardly, a split sleeve friction member frictionally engaging the inner tapered surface of said friction element, 25 said sleeve having friction lugs at its upper end extending radially outward and having their upper surfaces inclined downward and outward, 30 an upper plate having a flange and a depressed hollow boss provided with an axial opening in its bottom wall, said upper plate having an annular

inclined friction surface for engaging the inclined surface of said friction lugs, a spring seat engaging said friction lugs, a spring between said seats and a bolt extending through said axial openings for limiting the expansion of said spring. 5

5. A car bolster support comprising a pair of plates each having a curved surface on its inner face, a pair of telescopic friction sleeves between said plates, said sleeves each having means on its outer end, provided with convex surfaces 10 for forming ball and socket joint with the curved surface of the corresponding plates whereby said plates will remain in parallelism even though they are temporarily out of alignment and resilient means for restoring the parts to 15 normal position after release.

6. A resilient supporting unit for railway trucks comprising a pair of cylindrical telescoping friction members, one of said members being tapered, one of said members having a unitary 20 head with a convex outer surface, a flange associated with the other member, and a spring encircling said telescopic members between said flange and head, and a cap member having a curved bearing surface for engaging said convex 25 surface for forming therewith a ball and socket joint, and means for limiting the expansion of said unit and for seating said bearing surface on said convex surface during the operation of the unit. 30
